CLAIM

I claim the ornamental design for an arcuate V-shaped former for a stackable truss, as shown and described.

DESCRIPTION

FIG. 1 is an elevational view of the arcuate V-shaped former for a stackable truss, the rear view being identical;

FIG. 2 is a side view of the arcuate V-shaped former for a stackable truss, each side being identical;

FIG. 3 is a top view of the arcuate V-shaped former for a stackable truss; and,

FIG. 4 is a bottom view of the arcuate V-shaped former for a stackable truss.
